WELL-DRILLING MACHINE

Forest R. Stoll, Carey, Ohio

Application October 3, 1934, Serial No. 746,746

7 Claims. (Cl. 255—4)

This invention relates to well-drilling machinery and especially to that type of drilling apparatus in which the bit is operated by electromagnetic means. One object of the present invention is to provide means whereby the cuttings will be caught and removed from the drilled hole, and means are provided to prevent access of the cuttings to the electromagnetic elements. Another object of the invention is to provide a novel automatic valve at the lower end of the drill tube, and it is also an object of the invention to simplify the construction and arrangement of the parts to the end that the efficiency of the apparatus may be increased. An apparatus embodying the invention is illustrated in the accompanying drawings and will be herein-after fully described, the novel features being particularly defined in the appended claims.

In the drawings:

20 Figure 1 is a vertical section through the well-drilling apparatus.

Figure 2 is an enlarged vertical section of the bailer and the upper end of the inner shell.

Figure 3 is an enlarged section through the 25 solenoids.

Figures 4 and 5 are enlarged detail sections showing different positions of the valve.

Figure 6 is a section on the line 6—6 of Figure 2.

30 Figure 7 is a section on the line 7—7 of Figure 2.

Figure 8 is a section on the line 8—8 of Figure 3.

Figure 9 is a wiring diagram of the well drilling 35 apparatus.

Figure 10 is a detail of a switch.

In the practice of the invention, there is provided an outer shell or tubing 1 that is let down in the drilled hole 2. At its upper end, the edge 40 of the shell 1 is bent inwardly, as at 3, and is secured upon a slightly conical flange 4 which is fixed upon an upper suspending tube 5 near the lower end of said tube. At the upper extremity of the tube, a bail 6 is secured thereto 45 and said bail is firmly attached to a suspending rod or cable, indicated at 7, which extends to the usual derrick at the mouth of the well. Disposed concentrically about the suspending tube 5 is a bailer cylinder 8 which is held in spaced 50 relation to and guided on the tube by a bracing spider 9. Both ends of the bailer cylinder are open and its lower end is flared, as shown at 10, so that it may rest upon the inturned edge of the shell 1, as shown in Figure 1, and openings 11 55 are formed in the tube at its upper end to be

used for lifting the bailer from its seat to discharge the cuttings. As the drilling proceeds, water or other liquid in the well will be forced upward between the shell 1 and the wall of the well to the upper end of the bailer or cylinder 5 5 at which point the current will lose its lifting force and the sand, silt and fine cuttings carried thereby will be deposited in the bailer, although the liquid may rise to the top of the tube 5 and return through the same and the shell 1 to the 10 bottom of the hole. When the bailer is filled, the entire device is drawn to the surface whereupon the bailer is slid upward on the tube 5, as shown in Figure 2, and the entire contents will be discharged onto the ground, the conical formation of the flange 4 expediting the outflow of 15 the material. The bailer is then returned to its seat on the shell 1 and the apparatus again lowered into the well for further operation.

The lower end of the suspending tube 5 is 20 flared, as at 12, below the flange 4, which forms the bottom of the bailer, and at its extremity has a radial annular flange 13, openings 14 being formed in the sides of the tube to facilitate the escape of liquid from the tube although the greater portion of the liquid will escape through the open bottom of the tube. Below the flange 13 and connected therewith and held in spaced relation thereto by the bolts 15 is a cap 16 closing the upper end of the inner cylindrical shell 17, and 25 within the shell and spaced below the cap is a guide plate 18 which is connected with the cap by bolts 19 and is also held in the shell by a retaining ring 20 engaged with the plate and the shell. The cap is provided centrally with a bushing 21 and the plate has a central opening 22 for the passage of a cable 23 carrying conductors which convey current to the several electrical elements which I am about to describe, 30 said cable extending from a source of electrical 35 energy through the tube 5.

Within the inner shell, below the plate 18 is a plate 24 upon which is secured a frame 25 which supports a motor 26 for turning a rotary switch member 27, said member being carried by the 40 motor shaft 28. The motor shaft is journaled in the frame 25 and the plate 24 and the rotary switch member 27 carries diametrically opposite brushes 29 which engage and close circuits through quadrantly spaced contacts 30, 31, 32 45 50 and 33 mounted on the plate 24, and it may be noted at this point that the inner shell is filled with oil to a level above the switch in order to lubricate the switch and also transfer heat to the shell from the solenoids to be presently de- 55

scribed. It will also be understood that the switch and motor may be located on the ground, at the top of hole.

The plate 24 is of insulation and rests on the upper closed end of a brass tube 34 which extends to the bottom of the inner shell 17. Suspended from the plate 24 by coiled springs 35 is a signal coil 36 the core 37 of which is housed in the brass tube 34, and stops 38 depend from the plate 24 to arrest the upward movement of the coil and prevent the springs lifting it out of operative relation to the core. On the under side of the shell of the coil 36 is a contact 39 which is adapted at times to engage a fixed contact 40 on the top of the upper cap 41 of a solenoid 42. Normally, the contacts 39, 40 are apart and the circuit to the signal 43 is broken. As the drilling progresses, the bit will be above the bottom of the hole unless the shell be lowered to keep the bit in proper relation to the earth formation. When this condition exists and the bit is working free, the weight of the bit and the core carrying it, to which the core 37 is connected, causes a downward movement of the core structure, including the core 37. Inasmuch, however, as the coil is always charged when the apparatus is operating, the coil will follow the movement of the core downward and thus effect engagement of the contacts 39, 40 to close the signal circuit, as will be understood upon reference to Figure 10 which figure also shows the coil to be receiving current from the main line. The signal is, of course, located at the mouth of the well and may be a bell or a lamp. It will be active until the operator lowers the tubing to again bring the bit into contact with the earth's formation whereupon the signal circuit will be broken.

The cap 41 marks the upper end of a series of solenoids 42, 43, 44, 45 which are fitted in the shell 17 around the brass tube 34, as shown, and the inner solenoids 43, 44 being separated by an open space 46. The core for the solenoids is housed in the brass tube 34 and consists of upper and lower iron rods 46 and 47 and an intervening short brass rod 48, a brass or non-magnetic rod 49 connecting the cores 46 and 37. At the lower end of the solenoid 47 is a short non-magnetic rod 50. Upon referring to Figure 9, it will be noted that the contact 30 is in circuit with the solenoids 42 and 44, the contact 33 is in circuit with the solenoids 43 and 45, and the contacts 31 and 32 are in the return sides of the respective circuits. It will now be seen that as the rotor 27 turns it will close a circuit through the contacts 30, 31 and through the contacts 32, 33 so that the alternate solenoids will be alternately energized and the core will be reciprocated to lift the bit and then let it drop to cut into the soil formation. As many solenoids as desired may be employed.

The bottom cap 51 for the solenoids is firmly fastened to the bottom or lower end of the brass tube 34 and rests on a gasket 52 that rests on the top end of a ring 53 which is screwed or welded in the lower end of the inner shell 17; the lower end of the ring being closed by a cap 54 and bolts 55 being engaged in the caps 51, 54 to secure the parts together and firmly clamp the ring 53 in place. The non-magnetic member 50 is connected to the core to move therewith and is provided with an annular flange 56 at its lower end, and buffer springs 57, 58 above and below said flange cushion the respective strokes of the core when the drill is not hitting the bottom of the hole.

A stem 59 depends from the core through the cap 54 and through a free piston 60 which is fit-

ted in the lower end of the outer shell and has a central opening 61 of appreciably greater diameter than the stem which passes through it. Above the piston, a valve disk 62 is fixed on the stem and the bit 63 is secured on the lower end of the stem, an expansion spring 64 being coiled around the stem between and bearing against the piston and the head of the stem. On the up stroke of the core, the piston will lag behind the valve, by reason of its frictional engagement with the shell, and the valve will consequently uncover the opening 61, permitting the liquid which may be in the shell to escape, as shown in Figure 4. On the down stroke, the valve will seat over the opening in the piston and the piston and valve will exert pressure on the liquid below it so that the liquid will be forced up in the well around the outer shell to carry the cuttings to the bailer, as previously described. The free piston 60 and expansion spring 64 can be placed above the valve disk 62 and then the liquid and cuttings will be circulated in the reverse direction. The cuttings will be dropped into the bailer after leaving the top of the suspending tube 5.

From the foregoing description, taken in connection with the accompanying drawings, it will be seen that I have provided a very compact mechanism by which an effective reciprocatory movement will be imparted to the bit and cuttings will be washed to and caught at the upper end of the drill. The accumulated cuttings may be easily discharged and, except for the discharge of the cuttings and lowering the apparatus in the well, the operation is entirely automatic.

Having described my invention, what I claim is:

1. A well-drilling apparatus comprising inner and outer shells, means at the upper ends of the shells for suspending them in spaced relation, a bit below the outer shell, bit-reciprocating means in the inner shell including a stem depending through the outer shell and carrying the bit, a free piston in the outer shell around said stem, and a valve on the stem to establish and cut off flow through the piston.

2. A well-drilling apparatus comprising inner and outer shells, a free piston in the lower end of the outer shell having a central opening and having its margin in frictional engagement with the shell, a bit below the piston, bit-reciprocating means in the inner shell including a stem passing through the opening in the piston and carrying the bit, an expansion spring between the piston and the bit, and a valve disk on the stem arranged to cover or uncover the opening in the piston.

3. A well-drilling apparatus comprising inner and outer shells, a bit below the outer shell, a series of solenoids in the inner shell, a core common to all the solenoids and carrying the bit, means at the lower end of the inner shell to cushion the strokes of the bit, a series of spaced contacts, the alternate contacts being in circuit with the similarly wound solenoids, a rotary switch successively engaging the successive spaced contacts, and a motor for driving said switch.

4. A well-drilling apparatus comprising a shell, a bit below the shell, electromagnetic means in the shell for operating the bit, a signal coil resiliently suspended in the shell, and a signal circuit controlled by said coil.

5. A well-drilling apparatus comprising a suspended tube, a shell depending from the tube and having a closed conical upper end, a cylinder on

- the tube and having a flared lower end fitting the conical upper end and resting thereon, cutting means carried by the shell, operating means for the cutting means and disposed within the shell, means at the lower end of the shell to cause cuttings to be washed up through the well into the cylinder, and the latter being slidably mounted vertically to provide and close a discharge space between the lower end thereof and the closed conical upper end of the shell.
6. A well-drilling apparatus comprising a suspended tube, a conical flange fixed on the tube near its lower end, an open ended bailer cylinder slidably mounted vertically on the tube, a shell depending from the flange and having an in-turned upper end following the shape of the flange and received thereby for cooperation therewith to close the upper end of the shell, said cylinder having a flared lower end shaped to fit said inturned upper end and resting thereon, cutting means carried by the shell, operating means for the cutting means and disposed within

the shell, means at the lower end of the shell to cause cuttings to be washed up through the well and into the cylinder, and the conical flange causing discharge of the cuttings when the cylinder is raised on the tube.

7. A well-drilling apparatus comprising a suspended tube having open ends, a bailer cylinder around the tube, inner and outer shells depending from the tube, the ends of the inner shell being closed, the upper end of the outer shell being closed, a bit below the outer shell, bit operating means housed in the inner shell, cooperating piston and valve means actuated by the bit operating means and disposed at the lower end of the outer shell for forcing cuttings through the well into the bailer cylinder, and the latter being slidably mounted vertically to provide and close a discharge space between the lower end of the bailer cylinder and the closed upper end of the outer shell.
